DESIGN FOR A BRASSIÈRE

Irving E. Pecknay, Brooklyn, N. Y., assignor to Divineform Brassiere Co., Inc., New York, N. Y., a corporation of New York

Application May 25, 1938, Serial No. 77,368

Term of patent 3½ years

To all whom it may concern:

Be it known that I, Irving E. Pecknay, a citizen of the United States, and resident of Brooklyn, New York, in the county of Kings, and State of New York, have invented a new, original, and ornamental Design for a Brassière, of which the following is a specification, reference being had to the accompanying drawing, forming a part thereof, and of which Figure 1 is a view in front elevation of a brassière as worn; Fig. 2 is a view thereof in rear elevation; and Fig. 3 is a view in end elevation showing my new design.

I claim:

The ornamental design for a brassière, substantially as shown.

IRVING E. PECKNAY,
